PAUL W. ENSIGN, OF LOS ANGELES, CALIFORNIA

CARBURETOR

Application filed April 8, 1926. Serial No. 100,489.

The general objects of the invention may be said to be to provide a carburetor having such a method of operation that the fuel requirements of an internal combustion engine may be fully satisfied under all conditions of normal running, idling, or sudden acceleration or deceleration. The manner in which I accomplish these objects, and further and more specific objects, and corresponding accomplishments of the invention, will all be best understood from the following detailed description of a specific, preferred and illustrative form of the invention, reference for this purpose being had to the illustration of a carburetor in the accompanying drawings, in which:

Fig. 1 is a plan partly broken away and in horizontal section, taken as indicated by line 1—1 on Figs. 3 and 4, and showing a carburetor equipped with my invention in its present preferred form;

Fig. 2 is a side elevation and vertical section taken as indicated by line 2—2 on Fig. 1;

Fig. 3 is a sectional elevation taken as indicated by line 3—3 on Fig. 1;

Fig. 4 is a central vertical section taken as indicated by line 4—4 on Figs. 1 and 3;

Fig. 5 is a detailed section taken as indicated by line 5—5 of Fig. 3;

Fig. 6 is a side elevation partly in section taken as indicated by line 6—6 on Fig. 1; and

Figs. 7, 8 and 9 are diagrammatic illustrations showing the various air and fuel passages and illustrating the action of the carburetor under different conditions.

In describing my invention I shall first describe the structure and arrangement of the carburetor shown in the drawings and describe how the various passages are, in practice, built into the carburetor structure; and then I shall describe the functions and operations of the various parts.

The carburetor here shown has a main air intake at A, controlled by a choke valve B, the details of which need not be herein described. The intake delivers air into an upturning elbow C, and above the elbow C is a Venturi tube D that forms the lower part of main suction passage E in the upper part 50 of which control throttle F is set in the usual

manner. Above the throttle the suction passage connects to the engine intake manifold and that part of the passage is, therefore, here called the outlet.

The carburetor is provided with a constant level fuel chamber G, in which fuel is maintained at the constant level L by means of float M actuating a valve N, means being provided at O for depressing the float manually. All the parts so far described are more or less commonly known and need no detailed description here.

Elbow C has a sump P at its lowermost point and a suction tube R extends into that sump and connects at its upper end with a passage S which extends upwardly and connects with an idling by-pass hereinafter described; the function of the sump and suction tube being to pick up any liquid fuel that under certain circumstances may have gathered in the sump, and to deliver that fuel to the outlet at times when the throttle valve F is nearly closed. This particular provision of a sump and suction tube is, however, a part of the subject matter of application, Serial Number 40,532, carburetor, filed June 30, 1925, by O. H. Ensign, and is not, in itself, a subject of the present invention.

Fuel chamber G is closed against external atmosphere and arrangements are made so that pressure from intake A is put upon the fuel in chamber G. This is done by a balancing means comprising a tube T presenting its end to the air current in intake A and connecting with an annular passage U which in turn connects with passage V (see Figs. 1 and 6), passage V communicating with fuel chamber G through a nipple W. By this provision the air pressure on the fuel in chamber G is made to depend upon the pressure and velocity at intake A; but this particular provision is a subject matter of Letters Patent No. 1,506,229, issued to O. H. Ensign on August 26, 1924, entitled "Carburetor", and is not, in itself, the subject matter of the present invention.

The carburetor, as here illustrated, comprises three main castings, one of which (1) includes the air inlet, the elbow C, and the suction passage; another (2) comprising

mainly the fuel chamber G and associated parts; and a third (3) that includes control elements, the bore 10 and passage 15 etc. The three castings are joined together at the plane X by suitable bolts or cap screws shown at Y in Fig. 3; and in the plane face of the mixing chamber casting are cast or otherwise formed grooves or depressions to form, when covered by the joining face of casting 3, several of the passages hereinafter described.

Casting 3 has an upwardly extending bore 10 into the lower end of which a fuel riser 11 is screwed, the upper end of the riser having a circular fuel orifice 12 somewhat above the liquid fuel level L. This orifice is adjustable in effective size by the valve 13, which depends from the screw-threaded adjusting head 14. Riser 11 is, for the greater part of its length, smaller in diameter than bore 10, so that an annular passage is formed around the riser for passing fuel and air downwardly to the horizontal passage 15. The bore 10 and riser 11 form, in effect, an inverted trap over which the fuel is lifted by suction, as will be hereinafter described, the height of the trap being such that the fuel will not flow over it unless suction is applied to the upper end of the riser. At the same time bore 10 forms a suction chamber in which fuel is mixed with air that passes into the chamber from fuel chamber G through a restricted air bleeder port 16. This restricted air bleeder is formed as a separate screw-threaded bushing inserted in the casting, the size of its bore being accurately calibrated in order to adapt the carburetor to different motors, and to suit, in proportion, the other co-acting parts of the carburetor. Passage 15 communicates directly with a bore 17, in which fuel nozzle 18 is set, this fuel nozzle discharging directly into Venturi tube D; nozzle 18 being set in a plane radial to the Venturi tube and may point upwardly as shown, but not necessarily so. The diagonal angle of the nozzle may be varied to suit different motors; and the nozzle may be set horizontally in some cases.

The parts just above described form a fuel passage extending from fuel orifice 12 to the discharge point of fuel nozzle 18 into the venturi. It will be noted that, characteristically, this fuel passage first extends down and then has an intermediate low point or part in the passage 15, and it is from this low point that fuel is taken off into the accelerating well means hereinafter described.

Fuel nozzle 18 is provided near its discharge end with several small transverse ports 19 communicating with the lower end of an idling by-pass whose upper end communicates with the outlet. In the construction here shown this idling by-pass comprises an annular passage 20 formed in the body of the Venturi tube D; passages 21 and 22, and passage 23, which is formed partly in the face of the mixing chamber casting (as shown

in Fig. 3) and partly as a bore 23^a in the wall of passages. The upper end of the bore 23^a is plugged as at 24 and a small port 25 leads out from the upper end of bore 23^a into the outlet at a point somewhat above throttle F. The idling by-pass, thus formed, connects between the suction outlet and fuel nozzle of the fuel passage at a point near its discharge into the venturi.

An accelerating well means, comprising the elements about to be described, connects at port 26 with the lower part of the fuel passage and is provided at its upper end with suction filling means and a limiting means to limit the height to which fuel is raised. Briefly described in detail, this accelerating well means embodies the following parts. A rather large sized well 27 has a U-shaped lower end that extends to a point under the fuel passage and connects, through port 26, to the under side of the lowest part of that passage. At its upper end well 27 connects by way of a restricted port 28 with a chamber 29. Chamber 29 has a restricted bleeder port 30 that admits air controllably to the chamber. In this particular case, although not necessarily, bleeder port 30 admits air from the upper part of fuel chamber G where the pressure is, in this case, but not necessarily, controlled by the balancing means before described. Chamber 29 also has a restricted suction port 31 that communicates with passage 32 formed as a bore in the wall of the main suction passage, plugged at its upper end at 33, and having near its upper end a small port 35 extending to the outlet at a point somewhat above the throttle. Bleeder port 30 forms the fuel limiting means for the accelerating well; while suction port 31, etc., form the suction filling means for the well. The position of port 35 with reference to the throttle determines the fuel rise and drop in the accelerating well with relation to throttle opening and closing, as will be hereinafter pointed out; and the exact position of port 35 may be determined to suit any given motor. It may be placed closer to the throttle, as shown at 34 in Figs. 5, 7, 8 and 9; or, as will be explained, two such ports 34 and 35 may be used.

Both ports 30 and 31 are formed in separate screw-threaded bushings and their sizes are accurately calibrated to proportionately suit the other parts of the device and to obtain the function and actions hereinafter described. Without limiting the invention, but merely to give a clear idea of proportions that have been found to operate successfully, I may say that port 31 is about .028 inch diameter; port 30 somewhat less than $\frac{3}{2}$ inch diameter; ports 25, 28, 34 and 35 are about $\frac{1}{16}$ inch diameter; and port 26 about $\frac{1}{8}$ inch diameter. These figures are given for a carburetor of about the size shown in the drawings, using gasoline as fuel. The exact sizes

of course vary in applying the carburetor to different motors.

It will be understood that the small port 28 connects between the upper end of the accelerating well and the suction chamber 29. This port 28 is smaller than the air bleed port 30 which admits air to chamber 29, and is also smaller than the port 26 which connects the lower end of the accelerating well with the fuel passage 15. When the throttle has been suddenly opened, and creates the difference in pressures, as herein described, and, by that difference of pressures, has drawn the fuel downwardly out of the well and out through the fuel passage, then if the throttle remains wide open air will subsequently flow downwardly through the accelerating well and into the main fuel passage. Naturally, at that time when the same fluid (air) is flowing through all three ports 30, 28 and 26, it is the smallest one of these three ports which has the effective controlling action on the amount of air that will be drawn into the main fuel passage. Of course, the other two ports offer some frictional resistance to passage of the air that will pass through the smallest of the ports; but it is characteristically the sizing of the smallest port 28 that controls the rate at which air is, under these circumstances, drawn through the accelerating well and into the main fuel passage.

Figs. 7, 8 and 9 show in diagram the various ports and passages hereinbefore described. For the purposes of this diagram passages 32, 29 and 27 are illustrated as if they were in the same plane as passages 23, being illustrated offset in that plane merely for the purpose of simple illustration. And restricted port 30 is shown as if it communicated directly with the upper part of the fuel chamber G—that is, with an extension portion G¹ of the fuel chamber, which extension portion is shown in the diagrams merely to aid the illustration. Idling by-pass 23 is illustrated in the diagram as connecting directly to port 19, without the intervention of the small passages 21 and 22; and in the diagram the showing of separate bushing members has been eliminated, the bushing passages only being shown. All this has been done to simplify the diagram and to facilitate explanation of functions and operations.

When the carburetor is in normal operation with throttle valve F somewhat open, the engine running at a uniform speed, the flow of air through venturi D causes a suction to be exerted on fuel nozzle 18. That suction draws fuel up through riser 11 and also draws air in through bleeder port 16 into suction chamber 10. Fig. 7 indicates the normal operation. The flow of air is shown by dotted line arrows, the passage of fuel by full line arrows, and the passage of

mixed fuel and air by dash line arrows. The mixed fuel and air are drawn through the fuel passage—the annular passage around riser 11 and then through passage 15 and fuel nozzle 18—into Venturi tube D where this mixed fuel and air is mixed with air passing upwardly through the venturi. At the same time air is drawn into the fuel passage through the accelerating well, as shown in dotted line arrows.

Now suppose the engine to be idling, with throttle F substantially closed, as shown in Fig. 8. Under these conditions the main air flow through venturi D is very small and a much higher suction is, by reason of the throttle closure, put upon port 25 than is put upon the discharge end of nozzle 18. The relatively increased suction on the idling by-pass causes fuel and air to be drawn through the fuel passage and from it through ports 19, and to be delivered through port 25 into the outlet. This suction at ports 19 is also sufficient to cause air to flow from the interior of venturi D into nozzle 18 to ports 19, and thus to mix with the fuel passing through those ports. The suction is also sufficient to cause at the same time a considerable flow of air through bleeder port 16 into chamber 10 to mix with the fuel that is being drawn through orifice 12. Thus during the idling operation there is mixed air and fuel flowing to the idling by-pass through the fuel passage, and also air from the main suction passage; giving the engine a mixture of proper proportions in the small quantity required for idling or near idling operation. The reverse flow of air through the discharge end of nozzle 18 at idling prevents any fuel being discharged into the Venturi tube where it would be liable not to be taken up by the slow current of air passing therethrough and therefore would be liable merely to run down the wall of the air intake. The friction of air flow through nozzle 18 and through bleeder 16 is sufficient, even when the engine is idling, to cause enough depression in chamber 10 to lift the liquid fuel over the upper end of riser 11. The depression necessary, in the design here shown, to lift fuel from float chamber level L through orifice 12 and from horizontal passage 15 to the ports 19 is comparatively very small, the vertical lifts being small. The depression at port 25, with the throttle closed, is many times greater than that necessary to lift the fuel through 12 and also to 19 and then on up from ports 19 through port 25. Consequently ports 19 are made small as compared with nozzle 18 and bleeder 16.

The idling mixture is adjusted to proper proportion by regulating the degree of depression applied to the ports 19. This is accomplished by means of the passage 40 which bleeds air from the lower or entrance portion of the Venturi tube (from a point where the

air pressure, when idling, is substantially the same as that at the end of fuel nozzle 18); past the controlling valve 42, and through port 43, to the passage S, which passage, as I have before stated, communicates with idling by-pass 23. By opening the valve 42 the depression in by-pass 23 and therefore the suction on ports 19, is lessened; and the opposite is the case if valve 42 is closed down. (Passage S is shown diagrammatically in Figs. 7-9; its actual position and structure are shown in the other figures).

When the engine is idling or running at low speed and power so that it requires little fuel and the throttle is closed or near its closed position, the suction exerted upon accelerating well 27 by way of port 34 or 35 draws fuel up from the passage 15. It will be understood that when the engine is idling or working under small load, and consequently a small amount of fuel is being drawn through the fuel passage, the fuel and air mixture will more or less separate out and a part of the fuel with some air, sinking to the bottom of passage 15, will accumulate there and in the lower part of the accelerating well. This fuel flowing into the U-shaped lower portion of well 27 is drawn up into that accelerating well to fill that well and to rise through the restricted port 28, and will continue to rise through 28 until it fills the chamber 29 to the level of the restricted port 31. Upon a very small amount of fuel attempting to pass port 31, it in effect chokes that port, and the suction through 31 is so checked that the air through port 30 then satisfies said suction sufficiently to check further rise of the fuel. Only an extremely minute quantity of fuel will flow through 31 even when the bleeder port 30 is of such a size as to allow any fuel at all to reach 31. The bleeder 30 may be of such a size (as is sometimes desirable) that no fuel as liquid will be raised through 28. By either means the maximum amount of fuel stored in the accelerating well may be controlled. Any small amount of fuel which does pass through 31 is part of the idling fuel, the major portion of which at all times passes through the idling by-pass. During filling of well 27 some air is being drawn up into the well along with the fuel. This air passes on up through the well, carrying some fuel with it through 28 and 31, so that the engine will not stop while the well is filling. This air passage is only temporary, the well quickly accumulating enough fuel to fill it with liquid. The rate and amount of fuel rise in accelerating well 27 is governed mainly by the depression acting upon that well through port 28, that depression acting against gravity and against the depression in the fuel passage (passage 15). The depression in passage 15 is, as before stated, governed by adjustment of the valve 42. Consequently adjustment of the valve has an interaction on the acceler-

ating well with a result that is explained hereinafter. With any given combination of adjustments, port sizes, etc., the amount of depression communicated to the accelerating well depends on the throttle position and engine speed. With the throttle closed or nearly closed, at any engine speed, the depression is sufficient to raise fuel quickly to the top of the well. Generally speaking, the amount of fuel drawn up in the accelerating well depends upon engine speed and throttle position; at higher engine speeds a proportionately smaller closing movement of the throttle will cause fuel to be drawn up in the well, but the difference in action at different engine speeds is slight, due to the peculiar interaction of the depressions communicated to passage 15 through the accelerating well and the idling by-pass. This is explained hereafter. And at any given engine speed the height of the fuel level in the well is determined by the amount of throttle closure, with this limitation: that as long as the throttle remains wide enough open to keep the air flowing as indicated in Fig. 7 there is no fuel drawn up in the well, but a slight throttle closure may merely cause some fuel momentarily to drop out of the mixture in passage 15 and then be gradually picked up by the air flowing through that passage and the air flowing downwardly through the well.

By the arrangement of ports 31 and 30 as described, the maximum height of fuel in the well is limited and oscillation of the fuel level prevented, and all this is done without discharging solid fuel from the well into the outlet, as would be the case if air bleeder port 30 were omitted. If air bleeder port 30 were omitted, the solid fuel would be drawn on up through passage 32 and be discharged as liquid through port 34 or 35 into the outlet; and those ports would then define the limit to which the liquid fuel is raised in the well. But I prefer to limit the fuel height as before described; because the bleeder port 30 not only admits air to pick up fuel to limit the fuel height in the well and carry a little fuel into the suction outlet in admixture with air, but port 30, in conjunction with port 31, provides an easy and accurate means (by their proportionate sizes) of controllably reducing the amount of effective suction applied to the well and of making that suction such that different degrees of throttle opening or closure, causing change in the depression applied to port 35, will cause the fuel to be raised to different levels in the accelerating well. The full suction on port 35 at closed throttle, if applied unmodified to the accelerating well, would be sufficient to draw liquid fuel right on through 31, 32 and 35. By modifying the effective suction applied to the top of the well it is not only possible to limit the extreme height of fuel lift to a dimension that can be contained within a practicable carbure-

retor design, but also to make the control so delicate that different throttle positions will cause variations in the small fuel lift.

I have described the operation of the idling by-pass, and also of filling the accelerating well and the means used to control the operation of each and to limit the maximum amount of fuel that can be lifted into the well. The idling by-pass and well, however, have an interaction due to the fact that the depression applied to the top of the well must lift fuel not only against gravity but against the depression applied to fuel passage 15, which depression is applied in part through the idling by-pass. That interaction and its results will now be explained more fully.

Suppose a condition in which the throttle has just been closed and the well is empty. Depression is immediately applied through the idling by-pass to the fuel passage 15 and this depression in the main controls the depression for the time being in the fuel passage. At the same time a depression from the same initial source (above the throttle) is applied through the open well to the fuel passage. The resultant depression in the fuel passage is modified by the air bleed through the nozzle and by the air bleed through 16 near the initial fuel feed orifice 12. But, regardless of whether the depression applied through the idling passage is higher or lower than the effective depression applied to the fuel passage through the accelerating well, it is a fact that the depression in the fuel passage at the instant the throttle closes is higher than it would be if the fuel passage depression were applied through the idling passage or the well alone. Because, although the effective depression applied through the idling passage may be more than that applied through the accelerating well, yet with two suction applied to the fuel passage and a given amount of bleed (nozzle 18 and bleeder port 16) constantly applied, the depression in the fuel passage must necessarily be lower, when two sections are applied, than when one is applied.

The result is that at the instant the throttle is closed and the well begins to fill the depression in the fuel passage is somewhat higher than it is later, and therefore more fuel is drawn over at the initial feed orifice 12 immediately after the throttle is closed than is drawn over later as the well fills with fuel. The well begins, on throttle closure, to draw off the mixture of fuel and air from the fuel passage, and the suction through the accelerating well correspondingly and gradually decreases, but continues decreasing until the well has more or less filled up with froth and the charge in the well, cleared of air, has finally become clear fuel. During all the time the air is bubbling through the well, a certain amount of suction, although decreasingly, is applied to the fuel passage

through the well in addition to the suction applied to the fuel passage through the idling by-pass. Thus, during the time that the well is filling, an additional depression is applied to the fuel passage to draw over more fuel, more or less in proportion to the increased demand for fuel to fill the well; so that during the well filling period there is sufficient fuel available both for well filling and for continued engine operation.

During the time that air is thus passing through the well while it is filling, that air passes on up to the intake above the throttle and carries with it enough fuel to keep the engine running during the time that the well is more or less robbing the idling by-pass of fuel. In spite of the fact that the increased depression on the fuel passage is drawing over an increased amount of fuel, the filling of the well might, if the well did not pass on a part of its fuel to the engine intake, rob the idling by-pass of enough fuel to more or less interfere with satisfactory engine operation. But the moment the well fills and the liquid clarifies, then all suction through the well to the fuel passage is stopped; the well is then substantially full and whatever further fuel it draws from the fuel passage is drawn comparatively slowly on account of the well and the well passages being then filled with clear fuel. Finally the filling of the well is limited by the clogging of the suction passage and from that time on the fuel goes from the well to the engine intake and forms a very small proportion of the idling fuel.

The fact that the fuel at its initial feed into the fuel passage is mixed with air, makes the foregoing described operations possible; that makes it possible for the well, by-pass of air, during its filling, to apply extra depression to the fuel passage to draw fuel over faster than it would otherwise be drawn over, and at the same time to have air bubbling through the well during its filling to carry a part of its fuel to the engine intake during idling. And these features of operation are found to give an unusually smooth and continuous engine operation throughout periods of quick changes of throttle position, and are therefore found to lead to unusually high fuel economy.

Further it is to be noted, regarding the cooperation of the idling by-pass and the accelerating well, that the connection of both of them to the same fuel passage makes the well action more uniform at varying idling speeds than it otherwise would be. At varying engine speeds, with the same throttle position, the suction varies very greatly; and a fixed suction modifying or bleeding arrangement will not, in itself, make uniform the effective suction applied to the accelerating well. In my design, however, the accelerating well pulls its fuel up not only against gravity but

against the depression communicated to the fuel passage through the idling by-pass; which depression, originating at the same source as the suction applied to the accelerating well, varies with the effective well suction and thus makes the well action more nearly uniform. The result is that the well fills nearly to the same amount, and at substantially the same speed, at engine idling speeds 10 that may vary as much as from 180 R. P. M. to 750 R. P. M.

When the throttle is somewhat opened, lessening the depression on the well, the fuel level therein immediately falls; but in falling away from port 28 it causes port 31 to be freed of the clogging fuel and the effective depression on the well is therefore relatively increased—or, as it might be expressed, maintained without a sudden drop. Thus a small 20 opening of the throttle does not empty the well, the fuel therein finding a lower level and remaining stationary as long as the throttle position and engine speed remain the same. The fuel dropped out of the well 25 has gone back to the fuel passage to supply the engine with the extra fuel for acceleration; but the fuel remaining in the well is ready for further acceleration. The amount of fuel dropped out of the well on a partial 30 throttle opening will also depend on the load on the engine. If the engine is free to speed up quickly the amount of fuel dropped from the well is relatively small; but relatively larger if the engine is loaded and picks up 35 speed slowly. Thus, although the amount of fuel drop from the well depends on both engine loading and the amount and quickness of throttle opening, generally and usually a quick wide opening of the throttle will 40 immediately empty the well and cause the carburetor then to operate normally as shown in Fig. 7.

Fig. 9 shows the condition ensuing on opening of the throttle. The increased suction applied to the fuel nozzle at the venturi has decreased action of the idling by-pass and has increased the suction on the fuel passage; so that the accelerating well empties both under gravity, due to air admission at 30—and under increased suction from the fuel passage.

Ports 25, 34 and 35 are so placed with relation to the throttle as to obtain the actions herein described. With the throttle somewhat more widely open than is shown in Fig. 55, it will be seen that the depression above the throttle is applied to port 25 and to port 35, but not to port 34; while when the throttle goes to its most closed position as shown in Fig. 8, suction is then additionally applied to 60 port 34. From a consideration of the relative port placements, it will be readily understood that the degree of throttle opening or closure (at any given engine speed) is the operating factor that controls and varies the amount of 65 suction applied to ports 25 and 35; whereas it

is throttle "position" that controls the suction applied to port 34. With the throttle fully closed the full suction is applied to port 34, but with a slight opening movement of the throttle that suction is cut off, and remains cut off throughout further opening movement; whereas the suction on ports 25 and 35 is gradually decreased as the throttle is opened wider and wider. The combined effect of the two ports 34 and 35 is to place a 70 gradually increasing suction on the accelerating well as the throttle is closed down, and finally to rather abruptly increase that suction as the throttle goes finally to closed position. And the abruptness of this final increase is the more marked because, until the throttle very nearly reaches closed position, port 34, being below the throttle, functions as a bleeder to admit air and modify the suction applied to port 35; this bleeding function being cut off as the throttle passes port 34. Thus in the fully closed position of the throttle the accelerating well 27 has an additional depression applied to it that raises the liquid level high enough to pass up through port 28; while if the throttle is slightly open (in a position above port 34) the depression transmitted to port 28 is somewhat reduced to allow the liquid level to fall somewhat in the accelerating well 27. And, from what I say 80 regarding the different actions of ports 34 and 35, will be understood the control of accelerating well action that may be had by proper placement of a single port 35. If that single port is placed relatively high it acts to draw fuel up in the well even though the throttle be quite widely open, and, conversely, not to drop the fuel completely until the throttle is quite widely open. If placed lower 85 it drops the fuel at a smaller throttle opening. 90

The restriction at port 28 is made of such size that the size of the bleeder port at 30 may be determined to control the bleeding of passage 29, and therefore the effective suction placed on the well, without materially varying the rate of air flow through the accelerating well, through port 28, when the well is empty of fuel. The size of passage 26 determines the rate at which the accelerating well will be emptied and therefore the rate at which the excess fuel will be delivered into the Venturi tube during acceleration. The restriction at 28 (bleeder port 30 is larger) determines the rate at which air will flow through the accelerating well in normal operation. The restricted port 28 is, however, made large enough to pass air downwardly as fast or faster than the restricted port 26 can pass fuel into fuel nozzle 18, so that port 26, by its size, 100 controls the rate at which the accelerating fuel is delivered to fuel nozzle 18.

Throughout this description and the following claims I use the term "bleed" or "bleeder" to denote the action of a port or orifice that admits air to a chamber or pas-

sage for the purpose of relieving or modifying the depression therein. The terms are so used in the practical art.

It is, however, to be understood that I do not intend my invention to be limited by specific terms or particulars of arrangement and design, which I have here described in full detail in order that those engaged in the art may understand the invention by way of a complete understanding of one typical embodiment. Rather I intend the invention to be limited only as expressed in the following claims, which are to be read in their broad as well as in their specific meanings.

I claim:

1. In a carburetor having a constant level fuel supply chamber, an air intake, a main suction passage provided with a throttle, an outlet beyond the throttle, a fuel passage having therein fuel metering means; and communicating with the fuel supply chamber and discharging into the main suction passage; the combination of an idling by-pass connecting and transmitting suction between the outlet and the fuel passage, and an accelerating well means connecting at one end to the fuel passage and having suction filling means communicating with the outlet independently of the idling by-pass.

2. In a carburetor having a constant level fuel supply chamber, an air intake, a main suction passage provided with a throttle; an outlet beyond the throttle, a fuel passage having therein fuel metering means; and communicating with the fuel supply chamber and discharging into the main suction passage; the combination of an idling by-pass connecting and transmitting suction between the fuel passage and the outlet, and an accelerating well means connecting at one end to the fuel passage at a point further removed from the discharge end of the fuel passage than is the point of connection of the idling by-pass, and having suction filling means communicating with the outlet independently of the idling by-pass.

3. In a carburetor having a constant level fuel supply chamber, an air intake, a main suction passage provided with a throttle, an outlet beyond the throttle, a fuel passage having therein fuel metering means; and communicating with the fuel supply chamber and discharging into the main suction passage; the combination of an idling by-pass connecting and transmitting suction between the fuel passage and the outlet, and an accelerating well means connecting at one end to the fuel passage and having suction filling means communicating with the outlet independently of the idling by-pass, and said idling by-pass and said accelerating well means each having an independent controlling air bleed acting to control the effective suction applied to each of the idling by-pass

and accelerating well means, respectively, independently of the other.

4. In a carburetor having a constant level fuel supply chamber, an air intake, a main suction passage provided with a throttle, an outlet beyond the throttle, a fuel passage communicating with the fuel supply chamber and discharging into the main suction passage; the combination of an idling by-pass connecting and transmitting suction between the fuel passage and the outlet, and an accelerating well means connecting at one end to the fuel passage at a point between its communication with the fuel chamber and the point of connection of the idling by-pass, and having suction filling means communicating with the outlet independently of the idling by-pass, the suction filling means for the accelerating well including a small suction port, a fuel limiting means for the accelerating well comprising an air bleed to said small suction port, said air bleed being independent of the idling by-pass so that suction applied to the accelerating well from the outlet is independent of suction applied to the idling by-pass, and said air bleed being also independent of the fuel passage so that suction applied to the accelerating well is independent of suction applied to the fuel passage.

5. In a carburetor having a constant level fuel supply chamber, an air intake, a main suction passage provided with a throttle, an outlet beyond the throttle, a fuel passage communicating with the fuel supply chamber and discharging into the main suction passage, said fuel passage consisting of an inverted trap extending above the fuel level and over which the fuel is raised in metered quantity by suction applied to the fuel passage, and of a horizontally extending portion leading from the lower end of the inverted trap to the main suction passage, and an air bleed into the inverted trap portion of the fuel passage above the fuel level; the combination of an idling by-pass and an accelerating well connecting to the horizontal portion of the fuel passage and each having independent suction connection to the outlet and each communicating suction to the fuel passage.

6. In a carburetor having a constant level fuel supply chamber, an air intake, a main suction passage provided with a throttle, an outlet beyond the throttle, a fuel passage communicating with the fuel supply chamber and discharging into the main suction passage, said fuel passage consisting of an inverted trap extending above the fuel level and over which the fuel is raised in metered quantity by suction applied to the fuel passage, and of a horizontally extending portion leading from the lower end of the inverted trap to the main suction passage, and an air bleed into the inverted trap portion of the fuel passage above the fuel level; the combination of an idling by-pass and an accelerat-

- ing well connecting to the horizontal portion of the fuel passage and each having independent suction connection to the outlet and each communicating suction to the fuel passage,
- 5 5. the idling by-pass connecting to the fuel passage near its discharge end and the accelerating well connecting to the fuel passage at the under side of the horizontal portion and at a point between the inverted trap and the point of connection of the by-pass.
- 10 7. In a carburetor having a constant level fuel supply chamber, an air intake, a main suction passage provided with a throttle, an outlet beyond the throttle, a fuel passage communicating with the fuel supply chamber and discharging into the main suction passage, said fuel passage consisting of an inverted trap extending above the fuel level and over which the fuel is raised in metered
- 15 15. quantity by suction applied to the fuel passage, and of a horizontally extending portion leading from the lower end of the inverted trap to the main suction passage, and an air bleed into the inverted trap portion of the
- 20 20. fuel passage above the fuel level; the combination of an accelerating well supplied with fuel from the bottom of the horizontal portion of the fuel passage, said accelerating well being provided with suction filling means
- 25 25. 30 communicating with the outlet and also with air bleed controlling means independent of the fuel passage and its air bleed.
8. In a carburetor having a constant level fuel supply chamber, an air intake, a main suction passage provided with a throttle, an outlet beyond the throttle, a fuel passage communicating with the fuel supply chamber and discharging into the main suction passage, said fuel passage consisting of an inverted trap extending above the fuel level and over
- 35 35. 40 which the fuel is raised in metered quantity by suction applied to the fuel passage, and of a horizontally extending portion leading from the lower end of the inverted trap to the main suction passage, and an air bleed
- 45 45. into the inverted trap portion of the fuel passage above the fuel level; the combination of an accelerating well connecting with the bottom of the lowermost portion of the fuel passage and provided with suction filling means
- 50 50. connecting to the outlet, the connection of the accelerating well to the fuel passage being in the form of a U leading downwardly from the fuel passage and then upwardly into the accelerating well.
- 55 9. In a carburetor having a constant level fuel supply chamber, an air intake, a main suction passage provided with a throttle, an outlet beyond the throttle, a fuel passage communicating with the fuel supply chamber and discharging into the main suction passage; the combination of an accelerating well means restrictedly connected at its lower end with the lowermost point in the fuel passage
- 60 60. 65 and having at its upper end a restricted port and a suction chamber into which said port opens, suction filling means connected to said chamber through a restricted suction port and connecting with the outlet, an air bleed port also communicating with said chamber, the restricted connection at the lower end of the accelerating well forming a means of controlling the rate of liquid flow from the well to the fuel passage, and the restricted port at the upper end of the accelerating well being smaller than the air bleed port and than the restricted connection between the well and the fuel passage and forming a means of controlling the flow of air through the accelerating well to said fuel passage when the accelerating well is empty of liquid.
10. In a carburetor, a fuel supply chamber, an air intake, a main suction passage provided with a throttle, an outlet beyond the throttle, a fuel passage leading from the fuel supply chamber and comprising an inverted trap and a horizontal portion leading from the lower end of the trap and discharging into the main suction passage, an idling by-pass and an accelerating well connecting directly with the horizontal portion of the fuel passage and each communicating with the outlet beyond the throttle, whereby suction from the outlet is applied independently to the by-pass and well and each communicates suction to the fuel passage.
11. In a carburetor, a fuel supply chamber, an air intake, a main suction passage provided with a throttle, an outlet beyond the throttle, a fuel passage leading from the fuel supply chamber and comprising an inverted air bled trap and a horizontal portion leading from the lower end of the trap and discharging into the main suction passage, an idling by-pass and an accelerating well connecting directly with the horizontal portion of the fuel passage and each communicating with the outlet beyond the throttle, whereby suction from the outlet is applied independently to the by-pass and well and each communicates suction to the fuel passage, and means to bleed air controllably into the by-pass and well independently of each other, so that the effective suction applied to the by-pass and well are independently controllable.
12. In a carburetor, a fuel supply chamber, an air intake, a main suction passage provided with a throttle, an outlet beyond the throttle, a fuel passage leading from the fuel supply chamber and comprising an inverted trap and a horizontal portion leading from the lower end of the trap and discharging into the main suction passage, an idling by-pass and an accelerating well connecting directly with the horizontal portion of the fuel passage and each communicating with the outlet beyond the throttle, whereby suction from the outlet is applied independently to the by-pass and well and each communicates suction to the fuel passage, the lower end of

the accelerating well being U-shaped and connecting into the lower side of the horizontal portion of the fuel passage.

13. In a carburetor, a fuel supply chamber, an air intake, a main suction passage provided with a throttle, an outlet beyond the throttle, a fuel passage leading from the fuel supply chamber and comprising an inverted air bled trap and a horizontal portion leading from the lower end of the trap and discharging into the main suction passage, an idling by-pass and an accelerating well connecting directly with the horizontal portion of the fuel passage and each communicating with the outlet beyond the throttle, whereby suction from the outlet is applied independently to the by-pass and well and each communicates suction to the fuel passage, and means to bleed air controllably into the by-pass and well independently of each other, so that the effective suction applied to the by-pass and well are independently controllable, the lower end of the accelerating well being U-shaped and connecting into the lower side of the horizontal portion of the fuel passage.

In witness that I claim the foregoing I have hereunto subscribed my name this 26th day of March 1926.
